United States Patent Office

Des. 182,708
Patented May 6, 1958

182,708

VACUUM BOTTLE CASING

Carl Bramming, Nashville, Tenn., assignor to Aladdin Industries, Incorporated, Nashville, Tenn., a corporation of Illinois

Application November 13, 1956, Serial No. 43,746

Term of patent 14 years

(Cl. D58—8)

FIG. 1.

FIG. 2.

I claim:

The ornamental design for a vacuum bottle casing, as shown.
